(57) **CLAIM**

I claim, the ornamental design for a mini air spray gun body, as shown and described.

DESCRIPTION

FIG. 1 is a perspective view of a mini air spray gun body showing my present design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof;

FIG. 8 is a perspective view when in use; and,

FIG. 9 is another perspective view when in use.

The broken line showing in FIGS. 8 and 9 is included for the purpose of illustrating and forms no part of the claimed design.
